UNITED STATES PATENT OFFICE.

CHARLES F. WOOD, OF SUMMIT, NEW JERSEY.

DESIGN FOR A LETTER FOR JEWELRY.

SPECIFICATION forming part of Design No. 14,248, dated August 28, 1883.
Application filed June 23, 1883. Term of patent 7 years.

To all whom it may concern:

Be it known that I, CHARLES F. WOOD, of Summit, in the county of Union and State of New Jersey, have invented and produced a new and original Design for Letters, of which the following is a full, clear, and exact description.

Reference is to be had to the accompanying drawing, forming part of this specification, in which a face view of my newly-designed letter for jewelry is shown.

My design consists of a letter made of heads of grain—for instance, wheat-heads, rye-heads, oat-heads, corn-heads, &c.—*a*, which are formed on the stone *A*, either in relief or inlaid. The heads *a* may be made plain, or may be set with diamonds or other precious stones *B*. The grain-heads are arranged in different shapes, according to the letter to be produced, and may be arranged straight, or curved longitudinally, transversely, or diag-

nally. In order to counterbalance the grain-heads proper, the stems are provided with one or more leaves, *b*, at the ends opposite the heads.

The letters can be produced on any stone, or any substitute for stones or gems—for instance, an enamel plate, a plain metal plate, &c.

I claim—

1. The herein-described design for letters on jewelry, consisting of letters made of single imitation straws or grain-heads, substantially as set forth.
2. The herein-described design for jewelry, consisting of a letter made of imitation grain-heads, in which diamonds or other precious stones are held, substantially as set forth.

CHAS. F. WOOD.
